UNITED STATES PATENT OFFICE.

WILLIAM BRUEN, OF NEWARK, NEW JERSEY.

DESIGN FOR TRUNK CORNER-CLAMP.

Specification forming part of Design No. 5,924, dated June 11, 1872.

SPECIFICATION.

To all whom it may concern:

Be it known that I, WILLIAM BRUEN, of Newark, in the county of Essex and State of New Jersey, have invented a certain new Design for Corner-Clamps for Trunks; and I do hereby declare that the following is a full, clear, and exact description thereof, reference being had to the accompanying drawing and to the letters of reference marked thereon which form a part of this specification.

The nature of my design is fully illustrated by the accompanying drawing.

The general shape of my corner-clamp A is like an L, each arm being triangular or wedge-shaped, with ears *a a*, one on each side and one at the point, each ear having a countersunk hole for the passage of a screw to fasten the clamp to the trunk.

The outer surface of the clamp, except at the edges, is convex and corrugated, as shown, forming a neat ornament as well as clamp.

The clamps used at the bottom will have the lower arm, or that arm which passes under the bottom of the trunk, provided with an aperture, *b*, with ear *d* on each side for the attachment of the roller-frame. The point on this arm may be omitted, if so desired.

What I claim is—

The design for corner-clamp for trunks, as shown and described.

In testimony that I claim the foregoing as my own I affix my signature in presence of two witnesses.

WILLIAM BRUEN.

Witnesses:

F. A. JOHNSON,
A. R. WHITEHEAD.
